ELECTRICAL SWITCH

Harry Goodman, Britton, and Ralph M. Wolfe,
Oklahoma City, Okla.

Application June 23, 1943, Serial No. 492,172

7 Claims. (Cl. 200—33)

Our invention relates to electrical switches, and more particularly to switches in which an electrically conductive liquid is used for making and breaking an electrical circuit.

One object of the invention is to provide a liquid switch in which an electrical circuit will be completed or broken only after the expiration of a desired time from the moment at which the switch is actuated, in other words, a delayed action switch.

In some electrical systems it is desirable to close one electrical circuit, and then, after the lapse of a limited time, to have another circuit automatically become completed. In such systems it is usually desirable to have the two circuits open or break in reverse order to that in which they were closed. For instance, in an electrically powered humidifier system, it is necessary that the circuit to the motor for driving a fan be first closed, and then after the motor has had time to reach its operating velocity, the motor driving the atomizer must be started. (In some cases the atomizer is operated by compressed air or steam. In such cases, the atomizer would be placed in operation by opening an electrically operated valve.) When it is desired to halt operation of such apparatus, the humidifier must be stopped before the fan motor circuit is opened, in order to prevent flooding.

Consequently it is an important object of the invention to provide a liquid switch which will function to close two electrical circuits in timed relation, and which will function to break the circuits in reverse order to that in which they were closed, but also in timed relation to each other.

The present switch is designed to be operated to opened and closed positions by an electro-magnet or solenoid. Since most liquid switches use mercury as a contact making agent, and since mercury is extremely heavy, damage to the switch could well occur if the switch was to be thrown instantaneously by such magnetic apparatus.

It is therefore another object of the invention to provide a switch for the above described purpose, but in which has been incorporated a slow motion feature to prevent damage to the valve when it is operated.

Other objects of the invention will be apparent from the following description when taken in connection with the accompanying two-sheet drawings, wherein:

Figure 1 is a front elevational view, partially in section, showing a preferred form of the switch while in open, or circuit breaking position;

Figure 2 is a similar view of the switch while in circuit closing position;

Figure 3 is an elevational sectional view looking in the direction of the arrows from a point indicated by the line 3—3 of Fig. 1;

Figure 4 is a view similar to that of Fig. 3, but looking from the line 4—4 of Fig. 2;

Figure 5 is a fragmentary top view detailing the clamp bracket or clip for removably holding the liquid containers;

Figure 6 is a side elevational view detailing a gear used as a part of the switch;

Figure 7 is an end elevational view of the same gear; and,

Figure 8 is a vertical sectional view through a liquid container and valve which may be used in lieu of those detailed in Figs. 1 and 2.

Like characters of reference designate like parts in all the figures.

In the drawings:

The reference numeral 1 indicates as a whole a mounting element or support for the switch. In the present instance the support 1 has been illustrated in the form of a wall bracket having a flat base 2 adapted to be attached to a wall 3 by screws or bolts inserted through suitable holes 4. The support or bracket 1 further includes two spaced standards 5 projecting perpendicularly from the base 2 and preferably being made integral therewith. The free end of each of the standards 5 carries a conventional bearing 6, and the two bearings 6 journal for rotation a shaft 7. The shaft 7 extends in both directions for some distance beyond the bearings 6, and its free ends are each equipped with a spring clip 8 (Fig. 5) for removably retaining a liquid container. The liquid containers will be described in detail hereinbelow.

Intermediate the two bearings 6, the shaft 7 is provided with a toothed gear 9 which is freely and independently rotatable upon the shaft. One end face of the gear 9 is provided with a lug or boss 10 having an abrupt face 11. The gear 9 is kept from longitudinal movement along the shaft by any suitable or conventional means, not shown, but which may be a reduced diameter groove in the shaft or could be set-collars. In the rotative path of the lug 10, the shaft 7 is provided with a rigid outstanding lug or projection 12 adapted to be engaged by the face 11 when the gear is partially rotated upon the shaft as and for a purpose which is more fully described hereinbelow.

The shaft 7, between the bearings 6 is further

provided rigidly with an outwardly projecting weight 13.

As a means for partially rotating the gear 9, there is provided a toothed rack 14 which meshes with the gear 9 and the teeth of which are formed upon the lower portion of an iron core 15 of a suitable electric solenoid 16. The extreme lower end of the core 15 is equipped with an enlargement or weight 17 having an office more fully described hereinbelow. A guide-bracket 18, or a plurality thereof, is provided to insure proper meshing of the rack and gear.

The apparatus thus far described constitutes the mounting and actuating mechanism for two occlusive liquid containers which are designated respectively by the reference characters A and B, and which will now be described.

The container A consists of a hermetically sealed or closed hollow body 20 having an interior septum or partition 21 with a comparatively large central through bore or port 22, and a minute through bore 23, which might well be termed a by-pass. A ball valve 24 is provided adjacent one end of the central bore 22, and when the body 20 is in the position illustrated in Fig. 1, the ball 24 is adapted to gravitate into a position to close the bore 22. A suitable stop or cage 25 is provided for the purpose of limiting movement of the ball 24 away from the partition 21. The end portion 50 of the body 20, or that end which contains the ball 24, has two electrodes 26 and 27 piercing and hermetically sealed into the wall of the body, and lying in identical planes. Electric conductors 28 and 29 connect respectively the electrodes at points lying outside of the body 20. An electrical conductive liquid 30, such as mercury, is provided within the container A.

It may be readily understood that should the container A be inverted, the ball 24 would drop away from the position in which it closes the orifice 22, and the liquid 30 would then gravitate into and sufficiently fill the end portion 50 to form an electrical contact between the terminals 26 and 27. In Fig. 2 the container A is shown after it has been inverted from the original position as shown in Fig. 1.

The container B is identical with the container A except that the partition 21 has been inverted and the ball 34 is below the partition, or in other words is in the end portion 51 when the container is in the position shown in Fig. 1. In other words, when the ball 24 of the container A is in the closing position, the ball 34 of the container B is in its opening position.

Should the container B be inverted from its position as shown in Fig. 1, so as to bring the end portion 51 uppermost, the ball 34 therein would then seat and close the central orifice or port 22 in the partition. Seating of the ball 34 would prevent gravitation of the liquid below the partition, except by passage through the minute perforation or by-pass 23. By the same token, if the container was again inverted after the liquid had flowed out at the end portion 51 of the container B, the ball 34 would fall away from the partition and allow the liquid 30 to immediately pass through the central bore 22 back into the end portion 51 of the container.

The container B has two or more terminals 36 and 37 which may be bridged by the liquid 30 therein when the container is in the position shown in Fig. 2. It is pointed out that terminals 26 and 27 and the terminals 36 and 37 are located in similar ends of the containers A and B respectively. In installing the device in the system,

the terminals 26 and 27 are made a part of one electrical circuit while terminals 36 and 37 are made a part of a different circuit.

For the purpose of explaining the operation 5 of the device, and illustrating the function of the above described switch in two circuits of an electrical system, we will assume that the installation is made in a humidifying system. The system will consist of three circuits described as 10 follows:

1. A circuit in which a humidostat and the solenoid 16 are wired in series, the humidostat being adapted to close the circuit in order to energize the solenoid when humidity in the place 15 at which it is located becomes too low, and to open the circuit and de-energize the solenoid when the humidity reaches a desired high point;

2. A fan or blower circuit including a motor 20 driven fan, with opposite sides of the circuit being connected to the terminals 26 and 27, the wiring arrangement being such that the motor will be energized when the terminals 26 and 27 are electrically connected to each other; and,

3. An atomizer actuating circuit, of which the 25 terminals 36 and 37 form a part. In this circuit, the arrangement will be such that the electrical connection of the terminals 36 and 37 to each other will actuate a suitable liquid atomizer. This could well be done either by an arrangement 30 whereby an atomizer is powered by an electrical motor, or by an arrangement whereby closing the connection between the terminals 36 and 37 will open a valve in a liquid pressure line so as to operate the atomizer.

35 The word "humidostat," as used herein, refers to any instrument capable of automatically determining humidity or being influenced accurately by change in humidity in the room or place where it is located.

40 With the above three circuit system in mind, and with the switch mechanism in the position as shown in Fig. 1, there will be no electrical connection between the terminals 26 and 27 or between the terminals 36 and 37. The solenoid core 15 is at the lower end of its throw, indicating that the solenoid 16 is not energized. Therefore no circuit of the system is closed.

Should the humidity become such that the 45 humidostat closes the solenoid circuit, the core 15 of the solenoid will instantly be pulled upwardly. This upward movement will rotate the gear 9, causing the abrupt face 11 of the boss or lug 10 to be moved from contact with the projection 12 on the shaft 7. Such movement of the 50 lug 10 will release the shaft 7 to a partial rotation under the influence of the weight 13, which will swing from its upright position as shown in Figs. 1 and 3, to a depending position as it is shown in Figs. 2 and 4. The weight 13 is sufficient to overbalance the liquid 30 in the bottom 55 ends of the two containers A and B. The containers A and B are therefore inverted to bring the liquid 30 into the now upper ends of the containers.

60 At this instant of the operation, the ball 24 will be below the partition 21 and will fall away from the center bore or port 22, therethrough, permitting the liquid 30 to immediately flow into the lower end 50 of the container A and reach a 65 level therein sufficiently high to bridge the terminals 26 and 27, and thus close the second circuit of the system, i. e., the fan driving or blower circuit. This will start the fan motor.

At the instant of inversion, the ball 34 in the 70 container B will be above the partition, and

the liquid 30 thereabove will cause the ball 34 to seat and close the central bore through the partition. The liquid can therefore reach the lower end of the partition only by passing through the minute perforation or by-pass 23 therein. The minute perforation 23 in the partition 21 of the container B is of such a size, that a desired time must elapse before all of the liquid 30 in the container B will pass from the upper end 51 to the lower end of the container B in order to build up to a sufficient level to electrically connect the terminals 36 and 37 and thereby close the third circuit of the system, i. e., the atomizer circuit. In the container B as shown in Fig. 2, this time has elapsed and the third circuit has been closed. The system is therefore in full operation.

As stated hereinabove, the original partial rotation of the gear 9 causes the lug 10 to be moved away from the projection or lug 12 on the shaft 8, but when the shaft then rotates under the impetus of the weight 13, this projection again catches up with the face 11 of the weight 13 and remains in contact therewith during the time the switch is in the position shown in Fig. 2.

Suppose now that the system operates for a sufficient time to raise the humidity to the point at which the humidostat will break the first circuit and de-energize the solenoid 16.

The combined weight of the core 15 and weight 17 on the lower end thereof, is sufficient to overcome the combined weight of the liquid 30 in the two containers and that of the weight 13, and consequently the shaft 8 will be rotated to the original position, or that position which it originally assumed in Figs. 1 and 3.

This last described rotation of the shaft 8 is accomplished by action of the rack teeth 14 to rotate the gear 9, and rotation of the gear 9 urges the face 11 of the lug 10 against the projection 12 of the shaft 8. The containers A and B are consequently returned to the positions shown in Figs. 1 and 3. At this instant of the operation the liquid 30 will reside in the upper ends of the containers.

When the containers have thus been inverted from their positions of Fig. 2, the ball 34 in the container B will immediately fall away from the central bore of the partition 21 therein, and the liquid 30 in the container B will immediately flow into the then lower end 51 of the container B, thus breaking the electrical connection between the terminals 36 and 37. The atomizer circuit will thus be broken.

At the same instant of the operation, the ball 24 in the end portion 50 of the container A will seat over and close the central port 22 of its partition. The liquid 30 in the container A will thus be retained in the upper end thereof for the time it takes it to pass through the minute passage 23. The electrical connection between the terminals 26 and 27 will therefore not be broken until some time after the atomizer circuit has been broken.

From the above description it will be apparent that a liquid switch mechanism has been provided which, when originally operated will immediately close the second circuit of the electrical system, and which will then, after a time lapse, close the third circuit of the system. Also, that when again operated, the switch mechanism will first function to break the third circuit of the system, and after an elapse of time will automatically break the second circuit of the electrical system.

In most liquid switches the liquid used is mercury. Since mercury is a comparatively heavy material, and since solenoids act substantially simultaneously, the present switch operating mechanism has been arranged to be moved in both directions by gravity. This has been done in order to prevent damage to the containers, which damage might well occur if a direct connection were made between the shaft 8 and the solenoid 16.

Since, as stated above, mercury is a comparatively heavy liquid, the balls 24 and 34 must be made of some material heavier than mercury, such as gold, platinum, or the like. This fact renders the switch of Figs. 1 to 7 quite expensive, although not prohibitively so. For this reason a slightly different embodiment of the valve construction has been provided as an alternative. This embodiment is illustrated in Fig. 8 of the drawings.

In this embodiment a container C has its upper and lower ends separated by a partition 40 having a minute through perforation or by-pass 41 similar in office to the passage 23 of Figs. 1 and 2. Instead of the central bore 22 of partition 21, the partition 40 has a pipe 42 passing therethrough. The upper end of the pipe has a reverse end 43 terminating in a downwardly facing open end 44. The ball 45 is confined in a suitable cage 46 beneath and in vertical alignment with the open end 44 of the pipe 42. The ball 45 is made of some material which is lighter than the liquid 47 in the container 40.

In this embodiment, if the container C were to be inverted from the illustrated position, the liquid 47 would pass downwardly through the pipe 42, would float the ball 45 away from the open end 44 of the pipe 42, and would freely enter the then lower end of the container without obstruction.

If the container C were to be again inverted, or moved back to the position shown in Fig. 8, the liquid 47 would then reside in the upper end of the container. The ball 45 would now float upwardly and close the open end 44 of the pipe 42, and would remain in its closing position until such time as the liquid 47 could escape through the minute perforation 41.

The valve of Fig. 8 would reach the same result as that of Figs. 1 and 2, so far as operation of the device is concerned, but would make it possible to use a ball of lighter material than that of the liquid used in the containers.

It is anticipated that liquids other than mercury may well be used in the containers. It is also apparent that the valve structure need not be of the ball-type, but could well be constructed along the lines of any conventional check-valve.

While experiments have shown that the electrically conductive material 39 is preferably of liquid, it might well develop that some other flowable material could successively be used, for instance, it is probable that some powdered electrically conductive material would prove practical.

We claim:

1. In an electric liquid type switch: two closed containers; a partition in each container dividing the same into an upper and a lower compartment; a large and a small port through each partition; a gravity actuated check valve in each container for closing one end of the large partition port therein, said valves closable in opposite directions; a plurality of electrical terminals in the similar compartments of each container; and an

electrically conductive liquid partially filling each container.

2. In an electric liquid-type switch: two closed containers; a partition in each container dividing the same into an upper and a lower compartment; a large and a small port through each partition; a gravity actuated check valve in each container for closing one end of the large partition port therein, said valves closable in opposite directions; a plurality of electrical terminals in the similar compartments of each container; and electrically conductive liquid partially filling each container; and means for selectively moving the containers to partial rotation upon substantially horizontal axes.

3. In an electric liquid-type switch: two closed containers; a partition in each container dividing the same into an upper and a lower compartment; a large and a small port through each partition; a gravity actuated check valve in each container for closing one end of the large partition port therein, said valves closable in opposite directions; a plurality of electrical terminals in the similar compartments of each container; an electrically conductive liquid partially filling each container; and means for simultaneously moving the containers to partial rotation upon substantially horizontal axes.

4. In an electric liquid-type switch: two elongated closed containers; means for mounting the containers for simultaneous end over end rotation; a plurality of electrical terminals in similar ends of each container; a partition in each container separating the end portions thereof, said

partitions having a comparatively large port and a small passage therethrough; a gravity actuated check-valve in one container for closing and opening one end of the port in its partition; a check-valve in the other container for closing and opening the opposite end of the partition port; and an electrically conductive liquid partially filling each container.

5. Organization as described in claim 4, in which the mounting means includes: a horizontally journaled shaft; and a spring clip bracket at each end of the shaft for removably retaining a container.

6. A delayed action liquid switch for electrical apparatus including: two elongated containers for an electrically conductive liquid, both mounted for partial simultaneous end over end rotation upon a common axis; a plurality of electrical conductors in the similar ends of each container; a ported partition intermediate the ends of each container; a gravity actuated check-valve for the port of each partition, said valves closable in opposite directions; a by-pass for liquid in each partition; a conductive liquid in each container in sufficient quantity to bridge the conductors thereof; and means for selectively moving the containers to partial rotation.

7. Organization as described in claim 6, in which the last means includes: a mechanism for releasing the containers to partial rotational movement; and a weight for gravitationally causing such partial rotation.

HARRY GOODMAN,
RALPH M. WOLFE.
